A. ZÓŁTOWSKI

CAP LOCK

Filed June 18, 1921

FIG. 1.

FIG. 4.

INVENTOR
A. Zoltowski
BY
M. E. L. L. his ATTORNEY

UNITED STATES PATENT OFFICE.

ANTONI ZÓLTOWSKI, OF NEWARK, NEW JERSEY.

CAP LOCK.

Application filed June 18, 1921. Serial No. 478,770.

To all whom it may concern:

Be it known that I, ANTONI ZÓLTOWSKI, a citizen of Poland, residing at Newark, in the county of Essex and State of New Jersey, have invented certain new and useful Improvements in Cap Locks, of which the following is a specification.

The main object of this invention is the provision of a connector for tanks such as are used in connecting with torches, as for instance, the acetylene torch.

The above and other objects will become apparent in the description below, in which like-named characters of reference refer to like-named parts in the drawings.

Referring briefly to the drawings, Fig. 1 is an elevational view of a tank equipped with my connector.

Fig. 2 is an enlarged front elevational view of my connector.

Fig. 3 is an enlarged side elevational view of the same.

Figure 4 is an enlarged sectional view of the device as applied to a container top.

Referring now in detail to the drawings, the numeral 1 represents a tank containing a fluid under pressure, having the usual outlet stem 2 thru which extends a channel 3 terminating in an outlet port 4. Ordinarily there is difficulty in connecting the tube 14, leading to the torch, to the stem 2 over the port 4. However, my device overcomes this difficulty in a manner which will presently become apparent.

My device comprises a substantially U-shaped frame 5 having a cap 6 hingedly attached thereto. The extremity 7 of said cap is curved as shown to provide a support for a slidable pin 8 adapted to engage a tongue 9 on the adjacent leg of the frame. A set screw 10 is supported as shown in the cap 6, and is provided with a handle 11.

A tubular stem 13 projects from the lower end of the frame 1, containing a channel or passage 15 which extends thru the lower

portion of the frame, the stem terminating in a semi-spherical boss 17 having a port 16.

In use, the connector is opened by withdrawing the pin 8 so as to allow the cap 6 to be swung open, the screw 10 having been previously released so that the lower end of the same will clear the frame 5 when said cap is thus swung about its pivot. The device is then tilted into a position substantially at right angles to the axis of the tank 1, and slipped over the stem 2 so that said stem lies within the frame 5. The boss 17 is then brought against said stem so that the port 16 will register with the port 14. Finally, the cap is swung back again and the pin 8 is slid forward to lock said cap, and the handle 11 is turned so as to clamp the device securely against the stem 2, between the boss 17 and the screw 10. The tube 14 leading to the torch is commonly internally screw-threaded, so that the same may be screwed upon the tubular stem 13.

Thus it is clear that I have provided a connector for use as mentioned which minimizes the time and labor expended in the use of torches or other devices utilizing fluid under pressure in a portable tank.

I claim:

A tank connector comprising a pair of opposed uprights extending from a base, a stud containing an axial passage passing through the base, its screw threaded portion engaging the tank to hold the base rigidly thereon, a cap hinged to one of said uprights, a lug extending outwardly from the other upright, said lug having a recess in its under side, a slide carried by said cap engageable with the recess in said lug, a convex head on said stud communicating with the tank, and a screw in said cap adapted to force a tubular connecting element into engagement with the opening in said head.

In witness whereof I affix my signature.

ANTONI ZÓLTOWSKI.
